CHECK NUMBER COMPUTING AND PRINTING APPARATUS

Alton J. Torre, Woodbury, N.J., assignor to Radio Corporation of America, a corporation of Delaware
Filed Dec. 22, 1961, Ser. No. 161,593
1 Claim. (Cl. 235—61)

The present invention relates generally to character printing or recording.

The object of the invention is to provide a simple and inexpensive apparatus for printing information, such as a multidigit number, and a check digit for that information.

The apparatus of the invention comprises a group of digit printing elements, such as printing wheels, which are independently controllable. A group of members, such as rack and pinion gearing, is used to set the printing elements in position to print the digits desired. Another printing element, a check element, is driven by the group of members to a position such that the digit it prints added to the digits printed by the number printing elements always is an integral multiple of a preselected number.

FIGURE 1 is a schematic, front elevational view of a preferred embodiment of the invention; and

FIGURE 2 is a side elevational view of a portion including one of the printing elements of FIGURE 1.

Referring to the drawings, pinions 20, 22 and 24 are fixed to printing wheels 10, 12 and 14, respectively. The pinions and their printing wheels are rotatably mounted on shaft 18. The latter is fixed to a support, indicated schematically by symbol 19. Racks 26, 28 and 30 engage and drive pinions 20, 22 and 24, respectively. The guides 70, 72 and 74 maintain the racks and pinions in engagement and insure that the racks travel in the desired direction. The arrows 31 indicate the direction of rotation of the wheels 10, 12 and 14 in response to movement in the upward direction of the tooth racks.

Printing wheel 16, shown at the left, is substantially identical to wheels 10, 12 and 14. A drum 44 is fixed to wheel 16 and both the drum and wheel are rotatably mounted on shaft 18.

A flexible member 40, such as a cable or a string, is fixed at one end to drum 44 and at the other end to spring 100. The latter is connected to a fixed point shown schematically at 101. Cable 40 is wound around drum 44, and through pulleys 50, 52, 54, 56 and 58, and through apertures at the ends of racks 26, 28 and 30. When any one of the racks 26, 28 and 30 is moved in an upward direction, the cable 40 rotates the drum 44 and check wheel 16 in the direction indicated by arrow 41. The reverse occurs when any of the racks is moved in the downward direction.

Printing wheels 10, 12, 14 and 16 each have similar printing means, such as raised type, on their outer circumferential surface. For purpose of illustration, ten numbers, namely 0-9 are shown on each wheel. The printing medium may be a sheet of paper, tape or the like and is shown in FIGURE 2 as a tape 32, which passes next to corresponding portions of each of the wheels. For example, with the wheels in the position shown, the position of the tape may be such that the number printed on the tape is 9 038. The printing mechanism may include a plurality of hammers, one for each wheel, and a plurality of hammer actuating means, one for each hammer. One of the hammers 33, and one of the actuating means, coil 34, are shown in FIGURE 2. An inked ribbon 36 is shown in FIGURE 2, next to the hammer 33. However, ribbon 36 may be placed next to the printing wheel as long as the numbers on the printing wheels are rotated 180° on their vertical axis to present a mirror-like image. The tape, ribbon, hammers and coils are not shown in FIGURE 1.

2

Number indicating dials 60, 62 and 64 with digits 0 to 9 on the surface thereon are associated with the racks 26, 28 and 30, respectively. The pointers 80, 82 and 84, which are fixed to racks 26, 28 and 30, respectively, indicate the digits selected for printing on the three wheels. The pointers are manually controlled.

Spring 102 is loosely wound around shaft 18 and fixed at one end to printing wheel 16. The other end of the spring 102 is fixed to a support indicated by 103. The arrangement is such that the spring 102 tends to rotate printing wheel 16 in a direction opposite to the one which flexible member 40 and spring 100 tend to rotate the printing wheel 16.

The ratio of the diameter of drum 44 to the diameter 15 of pinions 20, 22 and 24 is such that the angle through which a gear rack rotates a printing wheel 10, 12 or 14 is the same as that through which the cable 40 rotates the printing wheel 16. This requires the drum diameter to be twice the pinion diameter with the drive mechanism 20 shown.

Cable 40 is wound around drum 44 a number of turns equal to the number of printing wheels, when all printing wheels 10, 12, and 14 are at the zero position. Any desired number of printing wheels is possible, however, only 25 three are shown in FIGURE 1, as a matter of convenience.

Initially all wheels are in the zero position. A number is selected for printing by moving the pointers 80, 82, 84 adjacent to the digits desired. The pointers move the gear racks and the gear racks position the printing wheels 10, 30 12, 14. The gear racks also drive the cable 40, effectively shortening its length, and thereby at least partially unwinding the cable from the drum 44. This causes the wheel 16 to rotate in the direction indicated by arrow 41. The arrangement is such that the sum of the digits selected on wheels 10, 12 and 14, plus the check digit on wheel 16 is always 10 or an integral multiple thereof. In the example illustrated, the digits to be printed are 9 038, giving a sum of 20 or 2×10. If the number 038 is changed to 039, for example, the check digit changes from 9 to 8 so that the sum remains 20.

Although number printing dials 16, 10, 12 and 14 have been shown to be identical, number printing dial 16 could have an opposite digit sequence to the one shown in FIGURE 1, such that the sequence 0, 9, 8, 7, 6, 5, 4, 3, 2, 1 45 is produced by a counterclockwise rotation. The flexible member 40 then would be wound around drum 44 in a direction opposite to the one illustrated in FIGURE 1, and that spring 102 would also be wound in the opposite direction.

50 While not part of the present invention, the printer shown may be used with automatic reading apparatus. The latter may include means for detecting a missing or illegible digit and for determining the correct digit by subtracting the sum of the remaining three digits from $n \times 10$. 55 The reading apparatus may also include means for automatically inserting the correct digit in what is being read.

What is claimed is:

In combination, a plurality of identical number printing wheels; a check number printing wheel; a plurality of 60 pinions, each fixed to a different number printing wheel; a drum fixed to the check number printing wheel; biasing means coupled to said check number printing wheel and tending to rotate the same in a given direction; a plurality of gear racks, each engaged with a different pinion for 65 rotating the pinions and printing wheels to different positions, each gear rack including a cable guide at its free end; a plurality of pulleys; and a cable which is fixed at one end to a chassis and which is looped through the pulleys and the cable guides of the gear racks, and around the drum on said check number printing wheel in a direction to oppose the bias imparted by the biasing means, and is fixed at its other end to said pulley, in such manner 70

that movement of any gear rack causes rotation both of the number printing wheel coupled to the gear rack and the check number printing wheel.
